CLAIM

The ornamental design for the beer tap extension as shown and described.

DESCRIPTION

FIG. 1 is a left, front perspective view of a beet tap extension, showing our new design;

FIG. 2 is a right, front elevation view thereof;

FIG. 3 is a left elevation view thereof;

FIG. 4 is a right elevation view thereof;

FIG. 5 is a rear elevation view thereof;

FIG. 6 is a front elevation view thereof; and

FIG. 7 is a top plan view thereof;

FIG. 8 is a top plan view thereof; and,

FIG. 9 is a left, front perspective view thereof in a condition of use.

The broken lines in the drawings depict environmental structure of the beer tap extension that form no part of the claimed design.
